Primary Examiner — Khawaja Anwar*Assistant Examiner* — Mojtaba Tehrani(74) *Attorney, Agent, or Firm* — Berg Hill Greenleaf Ruscitti, LLP.(57) **CLAIM**

The ornamental design for the firearm magazine base plate, as shown and described.

DESCRIPTION

FIG. 1 is a front perspective view of a firearm magazine base plate, showing my new design;

FIG. 2 is a front elevation view thereof;

FIG. 3 is a back elevation view thereof;

FIG. 4 is a right elevation view thereof;

FIG. 5 is a left elevation view thereof;

FIG. 6 is a top view thereof; and,

FIG. 7 is a bottom view thereof.

The broken line in the drawings depicts unclaimed portion of the plate only and forms no part of the claimed design.

1 Claim, 5 Drawing Sheets(56)
